(57) **CLAIM**

The ornamental design for a hose connector as shown and described.

DESCRIPTION

FIG. 1 is a perspective view of the front, top, and right side of a hose connector;

FIG. 2 is a perspective view of the front, top, and left side thereof;

FIG. 3 is a front view thereof;

FIG. 4 is a top view thereof;

FIG. 5 is a right side view thereof;

FIG. 6 is a left side view thereof;

FIG. 7 is an exploded perspective view of the front, top, and right side thereof;

FIG. 8 is a top view thereof shown in a state of use connected to the tubular body;

FIG. 9 is a cross-sectional view thereof taken along section line 10-10 of FIG. 8 shown in a state with the sleeve pushed in; and,

FIG. 10 is a cross-sectional view thereof taken along section line 10-10 of FIG. 8.

A rear view of the hose connector is omitted because the rear view is symmetrical to the front view.

A bottom view of the hose connector is omitted because the bottom view is symmetrical to the top view.

The broken lines in the figures indicate portions of the hose connector that form no part of the claimed design.
